UNITED STATES PATENT OFFICE.

OTTO FRICK, OF HERSERUD, SWEDEN.

ELECTRIC INDUCTION FURNACE.

Application filed January 16, 1922. Serial No. 529,734.

To all whom it may concern:

Be it known that I, OTTO FRICK, a citizen of the Kingdom of Sweden, residing at Herserud, Sweden, have invented new and useful Improvements in Electric Induction Furnaces, of which the following is a specification.

This invention relates to electric induction furnaces for melting and refining steel and other metals.

It is well-known that the greatest hindrance in continuously working such furnaces consists in the corrosion of the walls of the melting channel, which takes place especially at the inner wall of the channel and makes it necessary from time to time to interrupt the operation for repair. The said corrosion seems to an essential degree to depend on the rotation of the melting bath which is caused by the magnetic flux outside the iron core and takes place in every cross-section of the bath in such direction that the uppermost layer of the molten mass is continuously flowing against the inner wall of the channel. With the form of the cross-section of the melting channel usually used in induction furnaces in which the side walls of the channel are vertical or nearly vertical it is impossible to repair the walls of the channel during the working, as the repairing material cannot be made to adhere on the walls of the channel.

The object of the present invention is to remove said draw-back by an improved form of the cross-section of the melting channel.

The invention consists, chiefly, in giving to the inner wall or the inner as well as the outer wall of the melting channel such small inclination that it will be possible to apply and sinter on repairing material for repairing corroded parts of the melting channel when the furnace is tapped or by inclining the furnace during the operation so much that the corroded parts of the channel walls are uncovered.

In the accompanying drawing I have shown diagrammatically two embodiments of my invention. Fig. 1 shows a vertical cross-section of one embodiment of the invention and Fig. 2 shows a similar view of another embodiment.

Referring to the drawing, 1 is the iron core of the furnace, 2 the primary coil, 3 the ring-shaped hearth and 4 a cover on the hearth. According to Fig. 1 both side walls 5, 6 of the melting channel have such small

inclination that the cross-section of the channel has the shape of an open V. It will on account thereof be possible to repair the channel during the working of the furnace and especially when tapping the furnace by applying repairing material such as magnesite and the like on the parts of the channel walls which have been damaged by the molten bath. On account of the high temperature in the furnace said material is rapidly sintered and caused to adhere on the walls. Preferably the cover is for that purpose made in sections so that only a part of the channel need be uncovered when repairing shall take place or openings may be provided in the cover or the upper part of the hearth through which the repairing material can be introduced.

According to Fig. 2 the inner wall 5 only of the channel is made with small inclination while the outer wall which is in a less degree exposed to the corrosive action of the bath is essentially vertical.

In both of these figures it will be noted that the inclination of the sides subject to corrosion have an inclination to the horizontal of less than 45°. In other words, the inclination of the sides must be less than the angle of repose of the fettling material in order to be able to properly work the material at the places in the lining to be repaired.

What I claim is:—

1. Electric induction furnace, comprising a ring-shaped hearth having a melting channel the inner side wall of which has a less inclination to the horizontal plane than the angle of repose of the repairing material so that such repairing material can be applied and sintered on corroded parts of said wall during operation of the furnace.

2. Electric induction furnace, comprising a ring-shaped hearth having a melting channel in which both side walls have a less inclination to the horizontal plane than the angle of repose of the repairing material.

3. Electric induction furnace, comprising a ring-shaped hearth having a melting channel the inner side wall of which has an inclination less than 45° to the horizontal plane.

4. Electric induction furnace, comprising a ring-shaped hearth having a melting channel in which both side walls have an inclination less than 45° to the horizontal plane.

In testimony whereof I have signed my name.

OTTO FRICK
